UNITED STATES PATENT OFFICE.

THEODORE AMNELIUS, OF SOUTH FRAMINGHAM, MASSACHUSETTS.

PROPELLER.

936,508.

Specification of Letters Patent. Patented Oct. 12, 1909.

Application filed January 14, 1909. Serial No. 472,326.

To all whom it may concern:

Be it known that I, THEODORE AMNELIUS, citizen of the United States, residing at South Framingham, in the county of Middlesex and State of Massachusetts, have invented certain new and useful Improvements in Propellers; and I do hereby declare the following to be a full, clear, and exact description of the invention, such as will enable others skilled in the art to which it appertains to make and use the same.

This invention relates to propellers designed especially for use on aeroplanes or other forms of airships, but also applicable to any purpose for which a propeller may be employed.

The object of the invention is to provide a device in which each of the principal blades is formed of a plurality of vanes or sub-blades arranged in the manner hereinafter more fully set forth, in order that the efficiency of such blades and of the propeller as a whole may be greater than in a device in which the blades are of ordinary construction.

In the accompanying drawings: Figure 1 is a plan view of a propeller constructed in accordance with my invention, and Fig. 2 is a view taken at right angles to the view shown in Fig. 1.

Referring to the drawings in detail, 1 indicates the hub of my improved propeller, and 2, 3, and 4 designate the vanes or sub-blades used in the construction of each of the principal blades. Each sub-blade tapers from the inner to the outer end, being wider at such outer end, and is connected with the hub at an angle to the main axis of the hub, as shown in the drawings. The individual sub-blades are given a slight twist in order that the surfaces may be inclined to a greater degree toward the hub than at the outer ends, and each sub-blade contacts with the adjoining sub-blade at given points or rather along given lines, but are separated between these places of contact, permitting of the passage of the water or air between the blades.

Each vane or sub-blade consists of a plurality of sections 5, 6 and 7 curved on the arc of a circle, the end of such sections meeting along the lines 8. The parts 5, 6 and 7 are termed sections for convenience, but it will be understood that each sub-blade is preferably formed in one piece. The corresponding sections of vanes 2 and 4 are located opposite each other, but the sections of vane 3

are so arranged that the ends thereof contact with the middle portion of the arch of sections 5 and 6 of member 2, while the middle portion of the arches of vane 3 contacts with the ends of the sections of vane 4.

The various sub-blades are so proportioned and connected with the hub in such manner that a line joining any point on one edge of sub-blade 4 and a corresponding point on the opposite edge of blade 2 would lie in a plane perpendicular to the shaft 15, this line passing through the central portion of sub-blade 3.

A propeller constructed in the manner described construction in that it not only ordinary construction in that it not only produces the usual thrust, but the extent of surface acting on the air, or on the water, as the case may be, is materially increased without adding to the length or width of the blade. The parachute-like effect of the sub-blades or vanes, and the grouping of the latter, both contribute to produce this result. The spacing of the vanes permits of the passage of air currents between such vanes so that the several vanes of each principal blade are acting at a given instant upon an independent stratum of air perpendicular to the shaft.

What I claim as new and desire to secure Letters Patent on is:

1. In a propeller, a hub, a series of principal blades connected therewith, each comprising a plurality of sub-blades, each sub-blade arranged out of parallel relation with the adjoining sub-blade and formed with a contact portion whereby said sub-blades are spaced apart for the greater portion of their length.

2. In a propeller, a hub, a series of principal blades connected therewith, each comprising a plurality of sub-blades the sections of which are curved on the arc of a circle, each sub-blade being arranged out of parallel relation with the adjoining sub-blade and formed with a contact portion whereby such sub-blades are spaced apart for the greater portion of their length.

3. In a propeller, a hub, a series of principal blades connected therewith, each comprising a plurality of sub-blades formed of sections curved on the arc of a circle and contacting at intervals one with the other.

4. In a propeller, a hub, a series of principal blades connected therewith, each comprising a plurality of sub-blades, sections

of which present a convex surface on one side and a concave surface on the opposite side, the ends of such sections in one sub-blade arranged opposite the middle portion 5 of the sections of the adjoining sub-blade.

5. In a propeller, a hub, a series of principal blades connected therewith, each comprising a plurality of sub-blades, the edge 10 of one of said sub-blades being on a line with the opposite edge of an alternate sub-blade comprising a part of the same principal blade, such line being perpendicular to the main axis of the propeller.

6. In a propeller, a hub, a series of principal blades connected therewith, each comprising a plurality of sub-blades, sections 15 of which are convex on one face and concave on the opposite face, the edge of one of the sub-blades being on a line with the opposite 20 edge of an alternate sub-blade comprising a part of the same principal blade, such line

being perpendicular to the main axis of the propeller.

7. In a propeller, a hub, a series of principal blades connected therewith each comprising a plurality of sub-blades, sections 25 of which are convex on one face, and concave on the opposite face, the ends of sections of a given sub-blade arranged opposite the middle portions of sections of an adjoining sub-blade, the edge of one of said 30 sub-blades being on a line with the opposite edge of the alternate sub-blade comprising a portion of the same principal blade, such line being perpendicular to the main axis 35 of the propeller.

In testimony whereof I affix my signature in presence of two witnesses.

THEODORE AMNELIUS.
